UNITED STATES PATENT OFFICE.

FRIEDRICH HANNS GREVE, OF LA SALLE, ILLINOIS.

QUICK-ACTING WRENCH.

Application filed October 7, 1922. Serial No. 593,008.

To all whom it may concern:

Be it known that I, FRIEDRICH HANNS GREVE, a citizen of the Republic of Germany, and a resident of La Salle, in the 5 county of La Salle and State of Illinois, have invented a new and useful Improvement in Quick-Acting Wrenches, of which the following is a full, clear, and exact description.

10 My invention relates to improvements in quick acting wrenches of the type in which the jaws may be moved instantly into position, and it consists in the combinations, constructions, and arrangements herein described and claimed.

An object of my invention is to provide a device in which the jaws may be brought into clamping position and may be locked by the use of only one hand.

20 A further object of my invention is to provide a quick acting wrench in which a mere push on the handle causes the jaws to grip the object, such as a nut.

A further object of my invention is to 25 provide a quick acting wrench which can be inserted in a comparatively narrow space, due to the fact that the jaws are parallel with the axis of the handle instead of being at right angles thereto.

30 A further object of my invention is to provide a wrench which can be used in the dark, since the operator does not need to know the size of the nut or other object being turned.

35 Other objects and advantages will appear in the following specification, and the novel features of the invention will be particularly pointed out in the appended claims.

My invention is illustrated in the accompanying drawings forming part of this application in which—

Figure 1 is a plan view of the device,

Figure 2 is a sectional view, certain parts being shown in side elevation,

45 Figure 3 is an enlarged section along the line 3—3 of Figure 2,

Figure 4 is a section along the line 4—4 of Figure 2, and

50 Figure 5 is a section along the line 5—5 of Figure 2.

In carrying out my invention I provide a handle portion 6 consisting of a hollow cylinder which is closed at one end and which is provided at its opposite end with 55 a laterally extending triangular-shaped portion 7. The latter is provided with a slot

8 arranged to receive a milled thumb nut or wheel 9. The triangular portion 7 is also provided with a smooth bore 10 arranged to receive a screw 11 which is provided with a keyway adapted to fit over a key or feather 12. The construction is such that when the milled wheel is turned, it will cause the screw to travel along the bore without rotating.

60 The hollow cylindrical handle is adapted to fit over the cylindrical end 13 of a shank. Between the end 13 of the shank and the closed end of the handle is a spiral spring 14. The main body portion 15 of the shank 70 has a rectangular cross section, as shown in Figure 4. The shank has a slot 16 into which a pin 17 extends, the purpose of the pin being to limit the movement of the shank.

75 The outer end of the shank 15 bears a head 18, having an integral jaw portion 19. The head 18 is slotted to receive an integral extention 20^x of the companion jaw portion 20. The extention 20^x is pressed on 80 by a leaf spring 21 which is secured at 22 to the shank 15. The opposite end of the extention is engaged by the bow-shaped lever 23 which is fulcrumed at 24 on a bracket attached to the shank 15. The opposite end of the lever is adapted to bear on the inclined surface of the triangular extention 7 as clearly shown in the drawings. In order to provide for the smooth working of the parts, the leaf spring is bent to form 90 a rounded portion at its end, the ends of the extention 20^x are curved, and the ends of the lever 23 are rounded.

95 From the foregoing description of the various parts of the device, the operation thereof may be readily understood. Normally the jaws are open, being kept in this position by the spring 14 which forces the shank 15 forwardly, thereby permitting the spring 21 to push the extention 20^x downwardly (in the position shown in Figure 2) since the end of the lever 23 will swing inwardly, (i. e., upwardly) as the shank is pushed outwardly by the spring 14, the end of the lever riding on the inclined surface 100 of the triangular portion 7.

105 When it is desired to turn a nut or other similar object the jaw 19 is placed against the object and the handle 6 is pushed toward the nut as far as it will go. The movement of the handle with respect to the shank will cause the triangular portion 7 to move

the lever 23 so as to bring the jaw 20 instantly in position on the opposite side of the nut. The milled wheel 9 may then be turned so as to cause the screw 11 to engage the shank, thereby locking the jaws in position. When it is desired to release the jaws, the milled wheel is turned to force the screw 11 away from the shank and the spring 14 will instantly force the shank forwardly, thus opening the jaws.

It will be observed that the wrench may be, and is preferably manipulated by one hand. Thus, in Figure 1, the right hand could grasp the handle and the index finger would be underneath the wrench with the thumb on top, so that the milled wheel could be instantly turned as soon as the jaws had clamped the object. Since the milled wheel extends through the triangular portion 7, it could be used with the left hand as well as with the right, since it would only be necessary to turn the wrench over to bring it into position for the thumb and finger of the left hand to operate the milled wheel.

It often occurs that it is desirable to get into a small space to operate on a nut the size of which cannot be seen without a light. With my improved wrench all that is necessary is to insert the jaws open and push the wrench forwardly, when the jaws will clamp the nut in the manner already described.

I claim:

1. In a quick acting wrench, a shank having a fixed jaw thereon, a movable jaw slideable with respect to the fixed jaw, a telescopic handle portion slideable on said shank

and being provided with a beveled portion, a lever carried by the shank, one end of said lever being arranged to bear on the movable jaw, and the other end being arranged to be engaged by the beveled portion of the handle and means carried by said handle for locking the handle to the shank. 40 45

2. In a quick acting wrench, a shank having a fixed jaw thereon, a movable jaw slideable with respect to the fixed jaw, a telescopic handle portion slideable on said shank and being provided with a beveled portion, a lever carried by the shank, one end of said lever being arranged to bear on the movable jaw, and the other end being arranged to be engaged by the beveled portion of the handle, means carried by said handle for locking the handle to the shank, and a spring carried by the shank and arranged to engage the movable jaw to force it away from the fixed jaw. 50 55

3. In a quick acting wrench, a shank having a fixed jaw thereon, a movable jaw slideable with respect to the fixed jaw, a handle portion slideable on said shank and being provided with a beveled portion, a lever carried by the shank, one end of said lever being arranged to bear on the movable jaw, and the other end being arranged to be engaged by the beveled portion of the handle, means carried by said handle for locking the handle to the shank, a spring carried by the shank and arranged to engage the movable jaw to force it away from the fixed jaw, and a spring carried by the handle for forcing the shank and the jaws carried thereby away from the handle. 60 65 70

FRIEDRICH HANNS GREVE.
